UNITED STATES PATENT OFFICE.

CHARLES A. JAMES, OF PHILADELPHIA, PENNSYLVANIA.

COMBINATION TOILET-BOX.

1,394,837.

Specification of Letters Patent. Patented Oct. 25, 1921.

Application filed November 13, 1920. Serial No. 423,865.

To all whom it may concern:

Be it known that I, CHARLES A. JAMES, a citizen of the United States, residing at Philadelphia, in the county of Philadelphia and State of Pennsylvania, have invented certain new and useful Improvements in Combination Toilet-Boxes, of which the following is a specification.

One object of my invention is to provide 10 an improved combination toilet device which will be of particular value for use by travelers who wish to carry a number of toilet articles in a compact form; the arrangement of the parts being such that any of the articles 15 is readily accessible.

Another object is to construct my improved device in such manner that it can be easily and cheaply manufactured and will 20 present a device of convenience for the traveler.

These objects, and other advantageous ends which will be described hereinafter, I attain in the following manner, reference being had to the accompanying drawings in 25 which—

Figure 1 is a top plan view of my improved device,

Fig. 2 is a sectional elevation taken on the line 2—2 of Fig. 1 showing certain of the 30 parts in different positions from the positions shown in Fig. 1,

Fig. 3 is an inverted plan view of the device,

Fig. 4 is a fragmentary plan view showing certain of the parts in the position illustrated in Fig. 2, and

Fig. 5 is a fragmentary section taken on the line 5—5 of Fig. 1.

Referring to the drawings, 6 represents a 40 body portion which may be made of wood or other suitable material providing a comparatively wide part 7 and extension 8; said extension being of such shape as to form a handle. The top of the part 7 has a recess 45 9 in the bottom of which is positioned a mirror 10, and a lid 11 which is hinged at 12 is adapted when closed to cover and protect the mirror 10; a suitable clasp 13 being provided at a position opposite the hinge 12 in 50 order to hold the lid in its closed position. The body portion 6 is also provided on its top surface with an elongated recess 14 and within the recess is secured a coiled spring 55 15 which extends in an upright position as shown in Fig. 2.

A comb 16 is adapted to be positioned

within the recess 14; it being necessary to place one end portion of the comb upon the spring 15 to compress the latter in order that the comb will fit within the recess 14. 60 A cover 17 is hinged at 18 to the body portion 6 and this cover is adapted to form a closure, when in the position shown in Fig. 1, for the recess 14. Any suitable clasp 19 can be used to hold the cover 17 in a closed 65 position. However, it will be understood that the mere release of the clasp 19 from a position over the cover 17 permits the spring 15 to raise the comb and the comb will push the cover 17 into its open position and the 70 end portion 20 of the comb will be raised to such position that it can be easily grasped by the fingers and removed for the purpose of combing the hair.

The body portion 6 has a cavity 21 therein which extends substantially its full length and said cavity is closed with exception of an opening 22. A plate 23, which forms a part of the body portion 6, provides a partial closure for the cavity 21 and a brush 24 has its head 25 secured to the under surface of the body portion. The plate 23 is beveled as shown at 25^a at a position over a part 26 of the head 25 of the brush 24. A removable panel 27 is used for closing the opening 22 and this panel has a part 28 adapted to be inserted between the beveled surface 25^a and the adjacent part 26 of the brush head 25. The opening 22 includes a ledge 29 at a position remote 75 from the beveled portion 25^a of the plate and the panel 27 is adapted to engage said ledge so that a clasp 30 will serve to hold in place the end of the panel opposite the portion which fits between the beveled portion 25^a and the portion 26 of the brush head 25. Thus it is necessary, in order to close the opening 22, to insert one end of the panel in between the part 26 of the brush head and the beveled surface 25^a of 80 the plate 23, after which the panel can be pushed into engagement with its ledge 29 and the clasp 30 can be turned in position 95 as shown in Figs. 2 and 3.

A spring clip 31 is secured to the upper 105 part of the body portion 6 and this clip may be used to support a shaving brush 32. In order to protect the bristles of the brush 24, I preferably provide a casing 33 which may be made of sheet metal blocked in form 110 so as to be fitted snugly against the outer edge surface of the brush head 25 as shown

in Figs. 2 and 3. Thus, when it is necessary to use the brush, the casing 33 can be removed and the device may be used as a brush by grasping the handle 8.

5 The cavity 21 can be used for various purposes such for example as for holding a razor, finger nail file or other elongated articles necessary as toilet articles and the same can be conveniently and quickly used 10 and as the person completes the use of each article, the article can be placed within its proper recess or cavity and in this manner the articles will not become lost nor can they be used by other persons; thus privacy is 15 secured and persons can keep their own toilet articles for their own use even though riding in railroad trains or other public conveyances.

While I have described my improved device as being particularly adapted for use 20 by travelers, it will of course be understood that the same presents many advantages for use by persons who desire to keep their toilet articles in a compact form.

25 While I have described my invention as taking a particular form, it will be understood that the various parts of my invention may be changed without departing from the spirit thereof, and hence I do not 30 limit myself to the precise construction set forth, but consider that I am at liberty to make such changes and alterations as fairly come within the scope of the appended claims.

35 Having thus described my invention, what I claim as new and desire to secure by Letters Patent is:—

1. A toilet device of the character de-

scribed including a body portion providing a cavity and having a bottom plate 40 forming a partial closure for said cavity, said body portion having a part extended beyond said plate and providing a handle; a brush having a head secured to said plate, a part of the head of the brush projecting beyond one end of the plate, said end of the plate being beveled inwardly, said cavity having an opening extending from said end of the plate to a position stopping short of the outer end of the handle, said end of the 50 plate being undercut; and a strip for closing said opening and having a part adapted to be projected in between the head of the brush and said end of the plate; substantially as described.

2. A toilet device of the character described including a body portion having an elongated recess in one surface thereof; a cover movably secured to said body portion for covering said recess, said recess being adapted to hold an article; and a spring within said recess adapted to press laterally on said article at a position nearer one end than the other to push said article against said cover whereby when the cover 60 is opened the article will be pushed laterally in an inclined manner out of said recess; substantially as described.

In testimony whereof I have signed my name to this specification in the presence of 70 two subscribing witnesses.

CHARLES A. JAMES.
